US00D593860S

(12) **United States Design Patent**
Bradley et al.

(10) **Patent No.:** **US D593,860 S**
(45) **Date of Patent:** **** Jun. 9, 2009**

(54) **DISPENSER**

(75) Inventors: **Christopher Bradley**, Orinda, CA (US);
John Jamieson, Walnut Creek, CA (US);
Jeffrey Tilley, La Honda, CA (US);
John C. Crawford, Mahopac, NY (US)

(73) Assignee: **Colgate-Palmolive Company**, New York, NY (US)

(**) Term: **14 Years**

(21) Appl. No.: **29/306,216**

(22) Filed: **Apr. 4, 2008**
